United States Patent

Des. 235,553
Patented June 24, 1975

235,553

CONNECTOR PACKAGE

James Raymond Kunkle, Enola, Pa., assignor to
AMP Incorporated, Harrisburg, Pa.

Filed Feb. 20, 1973, Ser. No. 333,580

Term of patent 14 years

Int. Cl. D13—03

U.S. Cl. D26—1 A

Fig. 1

Fig. 2

Fig. 3

FIG. 5

FIG. 4

FIG. 1 is a perspective view of a connector package showing my new design;

FIG. 2 is a side elevational view thereof, it being understood that the opposite side is a mirror image of the side shown herein;

FIG. 3 is an end elevational view thereof, it being understood that the opposite end is a mirror image of the end shown herein;

FIG. 4 is a top plan view thereof; and

FIG. 5 is a bottom plan view thereof.

I claim:

The ornamental design for a connector package, substantially as shown and described.
